UNITED STATES PATENT OFFICE.

WILLIAM A. NEWMAN, OF MONTREAL, QUEBEC, CANADA.

ENGINE.

Application filed March 12, 1920. Serial No. 365,371.

To all whom it may concern:

Be it known that I, WILLIAM A. NEWMAN, of the city of Montreal, Province of Quebec, Dominion of Canada, a subject of the King 5 of Great Britain, have invented certain new and useful Improvements in Engines; and I do hereby declare that the following is a full, clear, and exact description thereof.

Heretofore many attempts have been made 10 to solve the problem of economizing fuel and at the same time increasing the efficiency of locomotives. Economizers designed to absorb heat from the waste gases of combustion and feed water heaters designed to 15 absorb heat from the spent steam exhausted from the cylinders are well known and have been in use for some years, but the loss of heat units from both sources, fuel combustion and steam expansion are well known to 20 be still extravagant.

The object of my invention is to solve this problem and considerably reduce the loss of heat from both of these sources.

The invention consists of primarily, a 25 heater adapted to cause feed water passing therethrough to absorb heat from both the exhaust steam for the engine and waste gases of combustion; and, specially, a casting forming a component part of the engine 30 structure, preferably the closure for the smoke box, and embodying therein water and steam conductors and passageways for the hot spent gases, particularly arranged to constitute a combined feed water heater 35 and exhaust steam receiver.

For full comprehension however of my invention reference must be had to the accompanying drawings in which similar reference characters indicate the same parts 40 and wherein—

Figure 1 is a side elevation of a locomotive equipped with my invention;

Figures 2 and 3 are fragmentary sectional views illustrating the manner in which the 45 opposite ends of the top group of feed water tubes are mounted and the direction of flow therethrough;

Figure 4 is a fragmentary side elevation of the front end of a locomotive barrel closed 50 by my improved feed water heater;

Figure 5 is a transverse sectional view taken on line 5—5 Figure 6; and

Figure 6 is a longitudinal sectional view taken on line 6—6 Figure 5.

Heretofore the principal defect in the feed water heater has been its loss of heat

by evaporation and although the efficiency of the engine is increased by using the smoke box gases to preheat the feed water, in order to do so economically a greater heating surface is required than is obtainable in the accepted design of locomotives, and it has been particularly impracticable for the same reason in the ordinary smoke box with the space limitations of the latter. By my invention 60 a very high percentage of the waste heat units in the smoke box gases and exhaust steam from the engines are absorbed and the efficiency of the engine is proportionately increased. I obtain this result by combining in a single member the essentials of the "feed water heater" and "economizer" and the exhaust steam receiver, whereby the heat units are absorbed from both exhaust steam and products of combustion and at the same time afford an exhaust steam receiver of 65 substantially large dimensions to absorb the pulsations and convert them into a steady or uniform draft without offering increased 70 resistance to the exhaust. This member is 75 substantially cast in one or otherwise formed integrally with the closure of the smoke box.

In the accompanying drawings the closure is indicated at 2. It is cast with a bulging middle portion 3 presenting an inward 80 chamber and having an encircling flange 4 of sufficient width to fit the largest diameter 85 of smoke box and permit of its being cut down to smaller sizes without interfering with the chamber. The chamber within the 90 closure 2 opens into the smoke box and accommodates a steam receiver 9 of hollow 95 annular form cast in one piece with or otherwise formed integrally with the closure. This construction and arrangement of parts 100 avoids the complication of the front and design. The steam receiver is spaced from the closure on all sides as at 10 to enable the exhaust gases to form a hot blanket around the receiver and consequently overcome in large measure the loss of the heat units which would occur if the steam receiver was in intimate contact with the outside wall of the closure and at the same time to superheat the exhaust steam. The usual 105 steam exhaust fitting within the smoke box is indicated at 15, and the exhaust steam is conducted from it to the top of the receiver successively through an inlet pipe 16 and a 110 passage-way of substantially U-form 17. The latter is formed integrally with the inner side of the receiver and its arms are

curved concentrically with the latter. The pipe 16 communicates with the forked passageway 17 at the bottom thereof and the latter in turn communicates with the top of the receiver through a pair of spaced ports 18. In order to utilize the discharge through the steam exhaust fitting in sucking the water of condensation from the receiver communication between the bottom of the latter and the fitting is effected by a pipe 19 of relatively small bore located beneath and parallel to the pipe 16.

The circulation of steam from the fitting to the receiver is as follows:

15 The steam is discharged through the fitting and a portion of it flows through pipe 16 in the direction of the arrows in Figure 6 and entering passageway 17 flows upwardly through the same on opposite sides of the central opening and enters the top of the receiver through the ports 18, the water of condensation being sucked out through pipe 19.

25 The exhaust gases are deflected downwardly and around the steam receiver by a deflector 5 the lower end 7 which straddles the steam exhaust fitting, a shorter deflector 6 secured to the underside of the barrel in a similar manner to the deflector 5 causes 30 the gases to eddy around the receiver to enable the latter to absorb a large amount of the heat units.

The steam receiver contains preferably two series of tubes for conducting the feed water therethrough, the series being disposed horizontally at the top and bottom of the receiver, the top group being indicated at 20 and the bottom at 21. To accommodate these series of tubes the integral member comprising the closure and steam receiver is provided with lateral top and bottom extensions 22, 23, 24 and 25 located on both sides and horizontally opposite. The extensions on the right of the closure 45 are closed by headers 26 and 27 and each contains a tube sheet 28 held rigidly in position against a shoulder 29 by an inwardly extending annular flange 30 formed integrally with each header. The extensions on 50 the left are closed by return headers 31 and 32 and cover plates 33 and 34. The tube sheet 35 within each of these latter extensions is not held rigidly in position, but is mounted within each extension with a sliding fit, the purpose of this floating arrangement being to permit of expansion and contraction of the tubes. The return headers 31 and 32 are mounted upon their respective tube sheets by steel bolts 80 with nuts 81. 55 The interior of each of the headers 26 and 27, is divided by a horizontally disposed ring 40 into two chambers 41 and 42, the former surrounded by the latter. An inlet connection 43 communicating with the 60 chamber 42 and an outlet connection 44 lead-

ing from the chamber 41. The ring 40 which is carried by each header and the adjacent tube sheet divides each series of tubes into inner and outer groups 45 and 46, the flow of water through the outer group being 70 from right to left, as the outer group communicates with the inlet chamber 42 while the flow through the inner group is in the reverse direction as the inner group communicates with the outlet chamber 41. A 75 circular groove 50 in each of the headers 26 and 27 accommodates the outer edge of the ring 40. A packing member (not shown) may be positioned in this groove if desired.

The pipe system for supplying the feed water to the heater and from the heater to the boiler consists of a suction pipe 60 extending between the tender and a centrifugal pump 61 the latter being driven by a steam turbine 62 connected to the cab turret 85 through a pipe 63 controlled by a valve 64. The feed water is delivered from the pumps to the inlet connection 43 on the header 27 through a pipe 65 controlled by a valve 66 operated from the cab. From the header 27 the feed water passes upwardly to the inlet connection on the header 26 through a pipe 67 and is finally delivered to the boiler through a pipe 70 controlled by a boiler check 71. 90

To prevent the connections between the tender and feed-water heater freezing up in winter the suction pipe line is connected to the pipe 70 through a bye-pass 82 controlled by a valve 83 within the cab. By opening the valve 83 some of the preheated feed water is caused to circulate through the pump and associated connections and maintain the temperature of the water being drawn from the tender above freezing. 100

The turbine 61 and pump 62 are not shown in detail as any preferred construction may be employed.

Operation:

When the pump 61 is set in motion the feed-water is sucked thereto from the tender through the pipe 60 and from the pump it is delivered to the bottom header through the pipe 65, into chamber 42 from which it passes from right to left through the outer group of tubes 46, the return header 32 at the opposite end of the tubes turning back the flow into the inner or central group 45 of the tubes which communicate with the chamber 41. From this chamber through outlet connection 44, the feed-water passes upwardly through pipe 67, the upper end of which is connected to the inlet connection 42 of the header, from this point the flow is identically the same as that which takes place in the bottom series of the tubes, the feed-water flowing from right to left through the outer group and from left to right through the inner group passing up- 115 120 125 130

wardly through outlet connection 44 through pipe 70 to the boiler.

As the feed-water travels back and forth through the tubes it picks up the heat-units 5 from exhaust steam superheated from contact with the exhaust gases within the closure. A constant supply of this exhaust steam is obtained from the steam exhaust feed 15 through pipe 16 and the forked passage 17, the steam entering the steam receiver through ports 18 and flooding the interior of the same, the water of condensation running out through pipe 19 and being blown out by the succeeding pulsations. 10 The exhaust gases of combustion are deflected into the open chamber within the closure by the deflectors 5 and 6 and form a hot blanket around the receiver, insulating the same from the colder wall of the closure. 15

20 What I claim is as follows:—

1. In a locomotive the combination with the smoke box thereof, a steam exhaust fitting, a feed water supply, of a feed water heater consisting of a chambered closure for 25 the front end of the smoke box, a hollow annular steam receiver within said closure, a series of feed water tubes within said receiver and extending across the bottom of the same, a second series of feed water tubes 30 within said receiver and extending across the top of the same, means effecting communication between the series, means effecting communication between said receiver and steam exhaust fitting, and means effecting communication between one of the series 35 and the feed water supply.

2. In a locomotive the combination with the smoke box, boiler and steam exhaust fitting, of a feed water heater consisting of a 40 chambered closure for the front end of the smoke box, a hollow annular steam receiver within said closure and formed integrally therewith and spaced therefrom to present an insulating space, said closure and receiver 45 having top and bottom lateral extensions on opposite sides thereof, a tube sheet within each of said extensions, transversely extending feed water tubes located within said receiver with their ends mounted in 50 said tube sheets, headers coacting with the tube sheets in directing the flow of feed water through the tubes, an intake connection between the exhaust fitting and the annular receiver, a condensation outlet connection 55 between said receiver and the fitting, means supplying feed water to the tubes and means conveying the preheated water to the boiler.

3. In a locomotive the combination with 60 the smoke box and steam exhaust fitting, of a feed water heater consisting of a chambered closure for the front end of the smoke box, a hollow annular steam receiver within said closure, tube sheets within the heater, straight transverse feed water tubes extending 65

through said receiver with their opposite ends mounted in said tube sheets, one of said tube sheets being mounted in fixed position and the other of said tube sheets being capable of movement relatively to the first mentioned tube sheet for the purpose of permitting expansion and contraction of the tubes, headers coacting with the tube-sheets in directing the flow of feed water through the tubes, means effecting communication between the said exhaust fitting and the steam receiver, and means for supplying feed water to the tubes. 70 75

4. In a locomotive the combination with a smoke box thereof and steam exhaust fitting; 80 of a feed water heater consisting of a chambered closure for the front end of the smoke box; a hollow annular steam receiver within said closure formed integrally therewith, said heater having oppositely positioned lateral extensions, a header in each of said extensions and having tube sheets, one tube sheet being fixed and the other capable of movement relatively to the first mentioned tube sheet for the purpose of permitting expansion and contraction, tubes having their opposite ends mounted in said tube sheets, one side of said headers having an inlet communicating with some of the tubes and an outlet communicating with the remainder of 90 the tubes, and the other header being constructed and arranged to return the feed water through the tubes whereby the feed water flows through some of the tubes in one direction and through the remainder in the reverse direction; means for supplying feed water to said inlet and means effecting communication between the said exhaust fitting and the steam receiver. 95 100

5. In a locomotive the combination with the smoke box, boiler and steam exhaust fitting, of a feed water heater consisting of a chambered closure for the front end of the smoke box, a hollow annular receiver within said closure and formed integrally therewith and spaced therefrom to present an insulating space, said closure and receiver having top and bottom lateral extensions on opposite sides thereof, a tube sheet within each of said extensions, transversely extending feed water tubes located within said receiver with their ends mounted in said tube sheets, headers directing the flow of feed water through the tubes, an intake connection between the exhaust fitting and the annular receiver, means supplying feed water to the tubes and means conveying the preheated water to the boiler. 110 115 120

6. In a locomotive the combination with the smoke box thereof and steam exhaust fitting having a lateral opening; of a feed water heater consisting of an annular steam receiver located at the front of the smoke box and permitting access to the interior thereof through its central opening, means 125 130

for conducting steam from the lateral opening to the top of said receiver, said means consisting of a conductor of substantially U-form formed integrally with the receiver and having the arms of the U disposed on opposite sides of the central opening therethrough and communicating with the receiver at the top thereof, and a conductor effecting communication between the bottom of the U conductor and the lateral opening in the steam exhaust fitting; and a conductor of relatively small bore effecting communication between the bottom of the steam receiver and the

said fitting whereby the water of condensation in the receiver is sucked out by a discharge of steam through said fitting; and a feed water conductor extending through said receiver. 15

In testimony whereof I have signed my name to this specification in the presence of 20 two witnesses.

WILLIAM A. NEWMAN.
